DESIGN FOR A SHOE

Herman B. Delman, New York, N. Y.

Application December 11, 1937, Serial No. 73,535

Term of patent 3½ years

To all whom it may concern:

Be it known that I, Herman B. Delman, a citizen of the United States, residing at Hotel Madison, Madison Avenue and 58th Street, New York, in the county of New York and State of New York, have invented a new, original, and ornamental Design for Shoes, of which the following is a specification, reference being had to the accompanying drawing, forming part thereof, in which

Fig. 1 is a plan view of a shoe showing my new design; and

Fig. 2 is a side perspective view of the same.

The slashes are substantially U-shaped and are inclined from the lower end to the upper end, and are of substantial width, as illustrated.

The upper or body portion is formed in a single piece. The heel is low and the sole thin.

I claim:

The ornamental design for a shoe as shown and described.

HERMAN B. DELMAN.
